(57) **CLAIM**

The ornamental design for a mount for electronic device, as shown and described.

DESCRIPTION

FIG. 1 is a top-rear perspective view of the design for a mount for electronic device;

FIG. 2 is a top view thereof;

FIG. 3 is a bottom view thereof;

FIG. 4 is a right-side view thereof;

FIG. 5 is a left-side view thereof;

FIG. 6 is a rear view thereof;

FIG. 7 is a cross-sectional view thereof;

FIG. 8 is a front view thereof; and,

FIG. 9 is a top-front perspective view thereof.

The broken line portions in the drawings are shown to illustrate environment only and form no part of the claimed design.

The ornamental design for a mount for electronic device can be configured for use in a vehicle. For example, the mount can be configured to be coupled to a vent, such as on an automobile. The mount can hold a phone, smartphone, or other mobile electronic device.
